UNITED STATES PATENT OFFICE.

ARCHIE G. HOHENSTEIN, OF NEW HAVEN, CONNECTICUT.

STEAM-BOILER.

SPECIFICATION forming part of Letters Patent No. 759,522, dated May 10, 1904.

Application filed June 1, 1903. Serial No. 159,687. (No model.)

To all whom it may concern:

Be it known that I, ARCHIE GERRY HOHENSTEIN, a citizen of the United States, residing at New Haven, in the county of New Haven and State of Connecticut, have invented or discovered certain new and useful Improvements in Steam-Boilers, of which improvements the following is a specification.

The invention described herein relates to certain improvements in the form or style of water-tube boilers described and claimed in application Serial No. 159,684, filed June 1, 1903, and is especially adapted for use in launches or small vessels.

15 The invention is hereinafter more fully described and claimed.

In the accompanying drawings, forming a part of this specification, Figure 1 is a front elevation of my improved boiler, a portion of the front casing being removed. Fig. 2 is a view of the rear end, partly in elevation and partly in section; and Fig. 3 is a sectional elevation transverse of the boiler.

In the practice of my invention the headers 1 have their lower ends connected to an equalizing-box 39, which is supported at its end by water-legs 40, which also serve as a supply of feed-water to the equalizing-box, the feed-water pipe 48 being connected, as indicated in Fig. 1, to these supporting-legs. The front ends of three series of tubes 5, 7, and 8 are connected to the headers 1, which are divided into two chambers by the partition 4 or into two series of single headers, as described and shown in application Serial No. 159,684, filed June 1, 1903. The tubes of series 5 have their rear ends connected to junction-boxes 6, from which extend also the other two series of tubes 7 and 8, as described

40 in the application referred to. The carrying capacity of the tubes 5 is made equal to or approximately equal to the combined capacities of the two series of tubes 7 and 8. To the upper portions of the headers are connected tubes 43, their rear ends being closed, and within these tubes are arranged baffle-plates 44, whose front ends extend transverse of the headers, while their rear ends stop short of the closed ends of these steam-tubes, 45 so that the circulation through these tubes

will be along the under side of one tube toward their rear ends, back toward the front end over the baffle-plates to the headers. Within the headers and below the baffle-plates 44 are formed baffle-plates 45, they being so 55 constructed and arranged as to practically insulate the tubes of the series 7 and 8 from the tubes of series 5. As shown, these baffle-plates 45 extend vertically from the point between the junction of the upper one of the 60 series of tubes 5 with the header and the point of junction of the lower one of the tubes 7 and 8 with the header.

In this construction the circulation will be from the equalizing-box 39 to the headers, 65 through the tubes of series 5 to the junction-boxes 6, through the tubes of series 7 and 8 to the headers, over the upper end of the baffle-plate 45, and down along the outer walls of the headers to the tubes of series 5. 70 By reason of the several traverses of the steam through the tubes 43 a thorough separation of the steam from the water and drying of the steam is effected. The upper ends of the headers are connected by elbows 46 with a 75 steam-pipe 47.

It will be understood that positions of the series of tubes 5, 7, and 8 may be reversed—i. e., the series of tubes 7 and 8 may be connected to the lower portions of the headers and 80 the series of tubes 5 to the upper portions of the headers, as shown and described in application Serial No. 159,684, filed June 1, 1903.

It is characteristic of this construction of boiler that the loop circulation is maintained, 85 the headers 1, having the vertical diaphragm arranged as stated, serving as an uptake and downtake.

As stated in the application Serial No. 159,686, the equalizing-box forms an arch for 90 the tops of the furnace-doors.

It is characteristic of this boiler that one of the series of tubes extend from what is practically one water-chamber and the other series of tubes from another chamber, the two chambers being connected so that there will be an uninterrupted flow of water from one to the other. This separation of the two currents of water in the headers by the baffle-plate or diaphragm is preferred, but not absolutely es- 95 100

sential, as two opposite currents can be established in a body of water, as is well known to those skilled in the art. This construction of boiler has also a characteristic found in all of 5 my improved boilers, the maintenance of a constant supply or head of water at the lowest point of the circulation—*i. e.*, at the lower ends of the headers. Hence none of the tubes can be cut out by short-circuiting the circulation. 10

I claim herein as my invention—

1. A water-tube boiler having in combination two connected water-chambers, three connected series of tubes extending from said chambers across the combustion-chamber, a feed-supply connected to one chamber, and a steam-pipe to the other chamber, substantially as set forth.

2. A water-tube boiler having in combination a series of headers, three connected series of tubes extending from said headers across

the combustion-chamber, one or more tubes extending from the upper portion of each header and baffle-plates or diaphragms extending across each header and into the tube 25 or tubes, substantially as set forth.

3. A water-tube boiler having in combination an equalizing-box connected to the water-supply, a series of headers having the lower ends connected to said box, three connected series of tubes extending from the headers across the combustion-chamber, one or more tubes extending from the upper portion of each header and a baffle-plate or diaphragm extending across each header and into the tube or tubes, substantially as set forth. 30

In testimony whereof I have hereunto set my hand.

ARCHIE G. HOHENSTEIN.
